CLAIM

The ornamental design for a combined waterstop and fiberboard holders for stay-in-place continuous forms for concrete wall fabrication, as shown and described.

DESCRIPTION

FIG. 1 is a perspective view of the combined waterstop and fiberboard holders for stay-in-place continuous forms for concrete wall fabrication shown broken away in the middle to indicate indeterminate length it being understood that the broken lines are for illustrative purposes only and form no part of the claimed design; FIG. 2 is a top or bottom plan view thereof; FIG. 3 is an elevation view of either side of the waterstop thereof shown separately for clarity of illustration; and

FIG. 4 is an elevation view of either end thereof.

FIG. 3

FIG. 4
